UNITED STATES PATENT OFFICE.

JOHN W. FREE, OF WOODLAWN, PENNSYLVANIA, ASSIGNOR TO JONES & LAUGHLIN STEEL COMPANY, OF PITTSBURGH, PENNSYLVANIA, A CORPORATION OF PENNSYLVANIA.

TIN POT.

1,415,166.

Specification of Letters Patent. Patented May 9, 1922.

Application filed April 22, 1921. Serial No. 463,520.

To all whom it may concern:

Be it known that I, JOHN W. FREE, residing at Woodlawn, in the county of Beaver and State of Pennsylvania, a citizen 5 of the United States, have invented or discovered certain new and useful Improvements in Tin Pots, of which improvements the following is a specification.

In the production of tin plate it is necessary to cause the suitably prepared plate of 10 steel to pass through a bath of molten tin, that it may become coated with that metal; and, in order to attain best results, it is desirable that the progress of the plate shall 15 from the moment of entrance into the tin pot to the moment of egress be continuous or substantially so. It is further desirable that the feeding in of successive plates shall be at regular and minimum intervals of time. 20 The last desideratum may manifestly be best accomplished by mechanical and automatically operating means. It is to the attainment of the ends just indicated that my present invention is directed.

25 Apparatus embodying my invention is illustrated in the accompanying drawings. Fig. I is a view in vertical section through a tin pot to which the feeding apparatus has been adapted and applied; Fig. II is a plan 30 view from above drawn to smaller scale; and Fig. III is a view to larger scale, corresponding to Fig. II, and illustrating a modification in detail.

Referring first to Fig. I, the tin pot 1 here shown is of familiar type. In use this 35 pot is filled, as will be understood, with a bath of tin, maintained by suitable heating means in molten condition. Upon the surface of the bath of molten metal floats a 40 layer of flux. Within the pot, beneath the surface of the tin when the pot is in use, is a guide 2, 3 for the advancing plate. The direction of advance is indicated by an arrow *a*. Plates successively introduced at the 45 right (as seen in Fig. I) into the guide are caused to advance through the guide by means of a pusher 4, which engages them from behind, and they are carried out from the tin pot by engagement between pairs of 50 wiping and spreading rolls 5. The pusher drives each plate in turn forward through the guide until its forward edge enters the roll pass, and there it is engaged and thence it is carried forward by entrainment be- 55 tween the rolls.

The first feature of invention to which I direct attention concerns the pusher construction, and particularly the means whereby the pusher is caused to reciprocate, and in the course of its reciprocation to be responsive to particular and peculiar conditions of service. The pusher 4 is substantially 60 arc-shaped, is carried by a weighted radial arm 6, centrally pivoted, which weighted arm is periodically swung against gravity 65 by means of a cam 7 borne by a driven shaft 8. It is the weight of the pusher mechanism, made effective by the proper shaping of cam 7, which is the plate-impelling force; it is the cam 7 which properly controls the 70 pusher in its gravitational downward movement, and which in turn raises the pusher again against gravity. In Fig. I the pusher is shown in full lines in retracted position, ready to engage a plate from behind and to 75 drive it forward through the tin bath. Cam 7 turns clockwise, and it will be understood that, as cam 7 turns from the position shown in full lines in Fig. I to the position shown in dotted lines, the pusher will advance to 80 the dotted-line position.

It will be observed of this means of effecting pusher reciprocation that the forward drive of the pusher is not positive; the parts are not coordinated in such way that, 85 as operation progresses, the pusher must advance. If, for fortuitous cause, resistance to plate advance increases, the pusher will stop, even though the rolls continue to turn. There will therefore be no accumulation of 90 damaged material. And this will come about without injury to the machine.

The plate driven by pusher 4 enters the pass between rolls 5 at a speed not greater than, and preferably substantially the same 95 as, the speed at which rolls 5 will carry the plate onward. It will readily be perceived that, if the pusher carried the plate into the roll pass at a speed greater than that at which the rolls carry it forward, an undesirable 100 tendency to buckling would be brought about; if, on the other hand, the pusher should not advance the plates at a speed substantially as great as that at which the rolls 5 dispose of them, there would be 105 failure to attain the possible maximum rate of production. Such a condition as that last indicated is of course quite possible but ordinarily it will be preferable to produce at maximum rate. Two factors contribute 110

to the speed of pusher advance: one, the relative speeds of rotation of rolls 5 and of cam-shaft 8, and, the other, the particular shaping of cam 7. The rolls 5 and the cam 5 shaft 8 may be driven from a common source of power, and thus rendered interdependent in this matter of speed; or they may be independently driven, in which case speeds will be properly controlled and adjusted.

In the shaping of cam 7 account may be taken of something more than merely causing the plate to reach rolls 5 at a certain speed. The engineer will realize that this 15 pusher must recede after it has advanced, and that while it is receding the plate which it has last delivered to rolls 5 is being carried away. In order to save time in operation it will ordinarily be found advantageous to so 20 shape cam 7 that the retraction of the pusher will be at much greater speed than its advance, and further to accelerate the speed during the initial part of the advance (relatively to that during the concluding part), 25 to the end that each newly introduced plate shall as it begins its passage through the tin pot catch up to the preceding plate, and shall assume the slower speed only as it approaches rolls 5. In the machine which I 30 have built and put into operation the pusher 4 is withdrawn during one eighth of a rotation of cam 7 and advances during seven eighths of a rotation; during the first half of its advance the pusher moves at twice the 35 speed at which it moves during the second half. With these comments the matter of the shaping of cam 7 and the permissible modifications of shape will be understood.

In the retraction of pusher 4, it ordinarily 40 will have to pass above a newly entering sheet. I find it advantageous to mount pusher 4 pivotally upon arm 6, with a certain and conveniently narrow range of pivotal movement, and to provide a counter- 45 weight 9; the arrangement being such that the receding pusher will readily swing upward out of the path of plate advance, and when released will swing again to normal plate pushing position relatively to its carrying arm 6. Such swinging aside of the 50 pusher may be suitably effected—by engagement with the newly entering plate, for example.

Fig. II shows the pot to be of such width 55 as to receive plates advancing in a plurality of paths side by side. There is a separate pusher for each path. The lower pusher of the two shown in Fig. II is in the full-line position of Fig. I, and the upper is in the 60 dotted-line position. The reader will observe of the bifurcated head of the pusher that, in the case of the lower of the two pushers of Fig. II, it appears greatly foreshortened, whereas, in the case of the upper, 65 it appears substantially in side elevation.

All these features of construction are known already to the art; it suffices to indicate them, without minute description. It is in combination with them that the additional and supplementary apparatus of my invention 70 is designed to operate.

Ordinarily successive plates are manually brought to position where the advancing pusher will engage them and carry them forward. There is disadvantage in this, because there is a scarcely avoidable interval 75 of time during which the plate rests partly submerged in the tin bath. Such a pause in the movement of the plate is apt to leave upon it an ineffaceable mark.

My apparatus provides for the mechanical feeding forward of the plate to the place where the pusher engages it. The feeding forward of the plate may be minutely timed and correlated to pusher movement, so that 80 there is no appreciable pause in the advance of the plate, from the moment it enters until it leaves the bath in the tin pot.

Adjacent the rim of pot 1 is a table 11, preferably inclined toward the pot, as 85 shown, to form a properly directed approach to the guide in the bath. On the upper surface of this table a plate to be tinned may rest, and from it the plate may be advanced, to proper position for engagement by 90 pusher 4.

Beneath the surface of table 11 (which conveniently is formed of steel beams and is of skeleton construction, as shown) is an 100 endless driving member, here shown in the form of a sprocket chain 12 carried on wheels 13, of which the lowermost is positively driven in anticlockwise direction, as seen in Fig. I. Chain 12 carries an outwardly projecting dog 14. Longitudinally 105 of the table slides a pusher 15. It is counterweighted, as indicated by weight 16; and under the influence of this weight it rests normally at the remote and upper end of its slideway. The pusher, however, is adapted 110 to be engaged periodically from beneath by dog 14, as the dog advances along the upper and down-grade reach of sprocket chain 12. By such engagement the pusher is carried 115 downward along its slideway, until the dog, receding as it rounds the lower sprocket wheel, releases the pusher and allows it to return, under the influence of its counter-weight, to its initial retracted position.

In Fig. I pusher 15 is shown in full lines at the 120 lower and advanced end of its range of movement, and in dotted lines at the upper and retracted end. The position of dog 14 in the figures is diagrammatic, in that it is not actually engaging pusher 15. Pusher 125 15 is as I have just said at the lower limit of its reciprocation. But in order to show the dog more clearly, it appears, not engaging the pusher as properly it does, but in 130 midway position along the table. In Fig.

II the upper of the two pushers shown is retracted, the lower is advanced.

Pusher 15 is so correlated in organization and in operation with pusher 4 that the ultimate position to which pusher 15 brings a plate is precisely the position in which pusher 4 comes into action upon it; and, furthermore, pusher 15 brings the plate to that critical position at substantially the identical moment of time when pusher 4 comes into play. There is no such pause as to result in an imperfect or blemished plate. The collocation of parts to effect this end is sufficiently indicated in the drawings and will without further explanation be understood. The time relation in the co-operation of the two pushers may be established by driving cam 7 and sprocket wheel 13 from a single source of power, the intervening parts being suitably proportioned. It suffices in this connection to note that in the machine of the drawings sprocket wheel 13 is borne by a shaft 17 driven from a shaft 18 by means of the sprocket connection 19, and it is shaft 18 which imparts rotation to cam shaft 8 also.

Table 11 is, as shown in Fig. I, sloping, and means are provided to prevent the free sliding of the plates upon table 11 in response to gravity, but at the same time to leave them fully responsive to the operation of pusher 15. I show in the drawings alternative means for accomplishing this end, and this alternative showing is made in exemplary manner, merely, and not with any implication that it is exhaustive.

Referring first to Fig. I, it will be observed of the plate-engaging extremities of the pronged pusher 15, that each is crotch-shaped, that the branches 21, 22 of the crotch diverge at a narrow angle, that the branches are pivoted one to the other and that pivotal movement is resisted by a spring 23. By such provision the operator, placing a plate on table 11 (pusher 15 being then retracted to the dotted-line position, Fig. I), and giving it a backward or upward edgewise motion, causes it to be caught by the spring tension noted. This spring tension is sufficient to hold the plate against the tendency of gravity to cause it to slide freely down the table, but it is not so secure, but that pusher 4, advancing in due time, dislodges the plate and carries it forward through the tin pot.

The alternative means, illustrated in Fig. III, are found in a magnetic device for holding the plate to the table. Two of the beams 24 of the table, made conveniently as has been said of rolled steel, and for immediate purposes made necessarily of magnetic material, are electrically insulated from the supporting structure. These two beams are electrically connected by a bar 25 of soft iron, around which bar the conductor

26 of an electric circuit is helically wound. The energizing of this circuit causes the beams 24 to attract magnetically a plate of steel laid on the table, and it is a matter of proportions to obtain a magnetic force sufficient to overcome gravity, and yet to allow the pusher 15 to perform its intended function.

Fig. II shows a tin pot to which a plurality of pathways for plates lead, so that successive lines of feed are established side by side. Manifestly the number of these may be increased, as desired.

The instrumentalities described may be modified at will, within the knowledge of the skilled engineer.

I claim as my invention:

1. In combination with a tin pot of a pusher adapted to reciprocate vertically, means for periodically elevating said pusher against gravity and alternately allowing it to descend by gravity, the arrangement being such that the gravitally impelled descending pusher engaging a plate from behind may impel it through the tin pot.

2. In combination with a tin pot of a pusher adapted to reciprocate vertically, a shaft bearing a cam which in the range of shaft rotation alternately raises the pusher against gravity and controls its descent under gravity and a pair of rolls, the parts so arranged that the descending pusher engaging a plate from behind advances the plate through the tin pot and into the pass between the rolls.

3. In combination with a tin pot of an arm pivoted to swing in vertical plane above the tin pot, and a pusher pivoted to the said arm, the parts so arranged and proportioned that the ascending pusher meeting a new-entering plate swings against gravity on its pivot from the path of plate advance and, passing beyond the rear end of the plate, swings under gravity to plate-pushing position.

4. In combination with a tin pot of a gravity impelled pusher, a pair of rolls to the pass between which a plate is by the pusher advanced and by the rotation of which an entrained plate is carried forward, and a shaft bearing a cam controlling the gravitational descent of the pusher the shape of the cam being such that as the plate advances under impulsion of the pusher to the rolls the speed of pusher advance decreases.

5. In combination with a tin pot and a feed table, means for advancing a plate in continuous progress across the table and through the tin pot, such means including a pusher reciprocable upon said feed table and a second pusher reciprocable in said tin pot, the two said pushers coordinated in their reciprocation and being so relatively placed that the pusher last named above may in its retracted position engage from the rear a

90

100

110

120

125

130

sheet when carried forward by the pusher first named in its advance to extreme forward position.

6. In combination with a tin pot, a feed table therefor, a counterweighted pusher adapted to be carried forward longitudinally of said table and to recede under gravity, and an endless dog-equipped member adapted to travel longitudinally of said table adjacent the path of said pusher and in its travel to engage, to carry forward and to release said pusher, substantially as described.

7. In combination with a tin pot, an inclined feed table leading thereto, means for advancing a plate down the inclined table, and means for restraining the advancing material from sliding freely in response to gravity, substantially as described.

8. In combination with a tin pot, an inclined feed table leading thereto, a feed member movable longitudinally of said table,

said feed member being equipped with a spring-backed grip for material, substantially as described.

25

9. In combination with a tin pot, a feed table and a pair of wiping rolls, means for advancing a plate across said feed table and into said tin pot, a gravity impelled pusher correlated in its descent with the means last named adapted to advance an introduced plate through the pot and to the wiping rolls, the said pusher being further correlated to the wiping rolls and adapted to advance a plate at a rate not exceeding that imposed by the wiping rolls upon a plate once introduced between them, substantially as described.
